UNITED STATES PATENT OFFICE

OTTO KRELL, OF BERLIN-DAHLEM, GERMANY

LANDING OF AIRSHIPS

Application filed February 14, 1929, Serial No. 339,859, and in Germany March 6, 1928.

The invention relates to the landing of airships or dirigibles of considerable size. In landing airships it is customary to tie the airship to the mooring tower and to await favorable wind and weather before hauling it down and running it into the stationary hangar, which is at such a distance from the tower that the tower and hangar do not interfere with one another. To transfer the airship into this hangar, it is necessary to detach its mooring gear from the tower and to haul the airship into the hangar by the help of a considerable number of men. Apart from the fact that this can be carried out in favorable weather only and a delay of many days might occur for this reason, so that a lot of time is wasted, it is necessary to employ a great number of men, who are used for this purpose only and, last but not least, the airship is always exposed to serious risks during such transfers.

All these drawbacks are effectively eliminated by mounting the mooring tower at one end of a rotatable hangar over the admission door. The leeside of such a tower is provided with a runway upon which a crab is adapted to run up and down to which is moored the nose of the airship. To transfer the airship into the hangar the crab with the nose of the airship attached thereto is run down the tower up to the centre of the admission opening or a vertical travelling crane forming a downward extension of the mooring tower. The airship may then be run into the hangar without the necessity of detaching it from the crab. The mooring mast over the entrance of the hangar must have a sufficient height and be able to withstand the pull which large airships exert upon it in a strong wind. Since, on the other hand the weight of the tower should be as low as possible, it is preferably constructed of lattice or trellis work with suitable braces.

This construction offers, however, a considerable resistance to the wind flowing along the hangar. In this way the tower sets up considerable strains at the points of attachment on the hangar and air whirls are caused, which might have a detrimental action upon the airship entering the hangar.

One object of the invention is therefore to enclose the tower or mast in an envelope of stream line shape or configuration or to construct the tower of sheet steel in such a manner, that the cross-section of the tower follows stream lines. In this way the disturbing air whirls are effectively avoided, the mooring is facilitated and the air pressure upon the tower reduced to a minimum.

The stream line shape of the shell of the mast demands a sharp edge at the lee side. Since, however, the crab with the nose of the dirigible attached to it sweeps along almost the entire length of the tower, the provision of such a sharp edge would be impossible. A further object of the invention is therefore to construct the shell at the leeside of the tower in such a manner that it may be swung open like a swing door or to provide it with sliding doors adapted to be slid back along the stationary portion of the tower in the direction against the wind. The part of the shell rendered movable in this way may be subdivided into a number of sections. The individual doors, each section consists of two, are by springs maintained in the position corresponding with the stream line shape. When the crab is vertically reciprocated along the mast, it opens at least the doors of two adjacent sections by means of suitably shaped guide rails mounted upon the crab and running along rollers attached to the wings of the door. The wings must open so far, that the nose of the dirigible moored to the crab does not touch them.

As soon as the nose of the airship has passed the wings of the door close again under the action of the springs and the wind, so that the stream line shape is resumed again by the tower.

It will be readily understood, that it is of course not necessary to subdivide the shell of the tower or mast at its leeside into sections, but that the entire shell or envelope of the leeside may, if circumstances make it appear more favorable, be swung open at once or pushed back along the stationary portion of the shell prior to starting the crab on its way. The closing of the leeside portion of the shell does in this case not take place automatically,

but is effected by the attendants after the crab with the dirigible has passed.

Another object of the invention is to provide means for attaching the nose of the dirigible to the crab travelling up and down the tower. The improved means satisfy all demands, which can be made upon them, because the dirigible can be easily attached to and detached from the crab, it can swing freely towards all sides and roll around its longitudinal axis, and the holding means can yet withstand with certainty the highest strains, which can possibly be developed. An easily detachable and yet powerful holding device is provided a breech or block which is used to close the bore of a gun. In this mechanism the steel block or bolt carries an interrupted screw subdivided along the circumference into, say 4, 6 or 8 sections and a similar nut with internal interrupted thread operates with this bolt. The holding device according to my invention consists of such a bolt provided with interrupted screw, thread attached to the dirigible and a nut fitting said bolt, mounted on the crab, so that the bolt may be introduced into the nut when the threaded sections of the bolt coincide with the threadless recesses of the nut.

If after the introduction of the bolt the nut is turned by the breadth of a threaded section, say through an angle of 90, 60 or 45°, the thread on both parts is thrown into engagement and participates in bearing the load. By providing a suitable number of threads, it is possible to provide the necessary shearing sections to deal with any load. Such a lock satisfies all requirements in regard to strength as well as simplicity and rapidity in operation. In order to give the dirigible the necessary liberty of motion this screw breech lock is suspended in the centre of a Cardan joint. It is necessary that the axis of the screw should be rotatably supported in the inner Cardan ring, in order to permit that the screw may be rotated independently of the Cardan joint. In order to enable the screw bolt provided with the interrupted screw thread to find the nut easily and correctly a guide funnel is disposed in front of the nut. This funnel is provided with guide slots. At the nose of the dirigible are mounted guide blades, which engage the slots in the funnel and turn the funnel and together with it the nut to such an extent that the threaded sections of the bolt face the recesses free from thread in the nut. As soon as the bolt has been completely introduced into the nut, the nut is rotated by means of a wormgear by hand, or by machinery through the width of a section, i. e., through a fraction of the circumference. The dirigible is then secured to the mooring tower. To transfer the dirigible from the tower into the hangar, it is necessary to make provisions to haul the dirigible down the tower. For

this reason the nose attaching mechanism just described is mounted upon a crab. This crab is adapted to travel along guides mounted upon the tower, as soon as the mooring cable has been removed from the nose of the dirigible. The crab is preferably driven by electric motors supplied with current from a storage battery mounted upon the crab. In this way it is possible to manage without drag cables with their tendency of sparking.

An embodiment of my invention is illustrated in the accompanying drawings, by way of example.

In the drawings are

Fig. 1, a cross-section through a stream line tower or mast with travelling crab and the movable door leaves. The position of the leaves of the door during the passage of the crab together with the head of the dirigible is indicated in broken lines.

Fig. 2, a cross-section through the open door leaves and the plan of the crab with the guide rails and guide rollers on a larger scale,

Fig. 3, the elevation of the parts shown in Fig. 2,

Fig. 4, a sectional side-elevation of the nose mooring mechanism,

Fig. 5, a part of the front elevation, and

Fig. 6, a sectional plan of the nose mooring mechanism.

Referring to Fig. 1 of the drawings, it will be seen that the shell of the tower or mast consists of a rigid part 1 on the weather side and of movable parts 2 and 2' on the leeside of the mast. The movable parts are adapted to be brought into the position indicated in dotted lines. They are subdivided into individual sections along the axis of the tower. The wings or leaves 8 and 8' of the doors, see in particular Fig. 2, are rotatable around the hinges 6 and 6', and are maintained in the closed or folded position conforming to stream lines, shown in dotted lines in Fig. 2, by springs 9 and 9', Fig. 3. When the dirigible is hauled towards the tower, the crab 3 is situated at the highest point of the tower. When it is desired to run the dirigible into the hangar, it is necessary to make the crab 3 descend along the tower or mast.

The crab 3 then opens the leaves 8 and 8' by means of the guide rails 4 and 4' mounted upon it against the resistance of the springs 9 and 9' to such an extent, that the point or nose S of the dirigible can be carried along the tower without touching the edges of the wings. To reduce the friction between the guide rails and the leaves or wings of the door rollers 7 and 7' are provided upon the leaves of the door and run along said rails. When the crab 3 has passed, the springs 9 and 9' automatically close the doors again so that the streamline contour of the tower is interrupted for short periods and a short distance

only in comparison to the entire length of the tower.

Instead of the enclosure of the trellis construction of the mooring tower the part 1 5 of the tower may consist of a sheet metal construction the cross-section of which adapts itself as closely as possible to stream lines.

The cable 10 (Fig. 4) is fixed in the nose of the dirigible S in any suitable manner. 10 The lock illustrated consists of the parts 11, 11' and 12. On the cable 10 there is further mounted a clamping member 13 provided with a slender and an obtuse taper 13' and 13''. By the obtuse taper 13'' the clamping 15 member 13 centers itself in the threaded hollow bolt 5 mounted in the nose of the dirigible S. The slender taper 13' facilitates the introduction of the screw bolt 5 into the guiding funnel 14 of the nut 15. In order to enable the screw bolt 5 to be so guided against 20 the nut 15 that its sections provided with thread 5', Fig. 5, coincide exactly with the bare sections 15' of the nut 15, guide slots 14' and 14'', Figs. 4 and 6, are provided in 25 the guide funnel 14 and cooperate with guide blades 16 mounted upon the nose of the dirigible S and the screw bolt 5, whereby the funnel is turned in its bearing 18 into the correct position and with it the nut 15.

30 When the screw bolt 5 by the aid of the funnel 14 has entered with its threaded portions 5' the bare portions or sections 15' of the nut 15, Fig. 5, the nut 15 is turned by means of the wormgear 17 and 17'. To enable this to be carried out the wormwheel 17' is connected with the nut 15 and the worm 17 with the funnel 14, Figs. 4 and 5. The nut 15 is supported within the funnel 14 by means of the balls 18'. The funnel is able to turn 40 upon the balls 18 within the inner Cardan ring 19'. Through this and the Cardan joint consisting of the Cardan rings 19 and 19', the nut 15, the funnel 14 and thus the nose of the dirigible S are freely movable in all directions except axially in the frame of the 45 travelling crab 3. The springs 20 and 21 are intended to maintain the funnel in the horizontal position as long as it is inoperative, i. e., does not hold a dirigible. The travelling 50 crab 3, Figs. 5 and 6 runs with its wheels 24 and 25 in the U-irons 26 and 26', which run along the mooring tower from the point to the ground or to the vertical transverse member forming the continuation of the tower 55 across the hangar and designed as travelling crane to haul the dirigible into the hangar.

Upon the U-irons 26 and 26' are mounted the racks 21 and 21' with which engage the pinions 22 and 22' of the crab 3. The pinions 60 22 and 22' are driven by electric motors E across the worm gears 23 and 23'. The electric motors E are fed from a storage battery, not shown in the drawing, mounted upon the crab and travelling with it.

65 Various changes and modifications may be

made without departing from the spirit of the invention or the claims, and I desire therefore that only such restrictions should be placed thereon as are imposed by the prior art.

I claim as my invention:—

1. In a mooring device for dirigibles, in combination, a rotatable hangar, a mooring mast of lattice construction mounted above the aperture of said hanger, a stream line shell consisting of sections of sheet iron enclosing said mast, a travelling crab adapted to move along said mooring mast in a vertical direction, means upon said crab for opening the sections of said shell to allow the passage of said crab, and to close said sections again after the passage of said crab, and an easily detachable mooring device for the dirigible capable of withstanding high tensional stresses and adapted to permit free motion of the dirigible towards all sides mounted on said crab. 75 80 85

2. In a mooring device for dirigibles, in combination, a rotatable hanger, a mooring mast of lattice construction mounted above the aperture of said hangar, a stream line shell consisting of sections of sheet iron enclosing said mast, a travelling crab adapted to move along said mooring mast in a vertical direction, guide rails upon said crab for opening the movable portions of the shell sections, springs tending to keep said sections closed and adapted to close them after said crab has passed, and an easily detachable mooring device for the dirigible capable of 90 95 100 withstanding high tensional stresses and adapted to permit free motion of the dirigible towards all sides mounted on said crab.

3. In a mooring device for dirigibles, in combination, a rotatable hangar, a mooring mast of lattice construction mounted above the aperture of said hangar, a stream line shell enclosing said mast and consisting of sections comprising a stationary and a portion movable, a travelling crab adapted to move along said mooring mast in a vertical direction, means upon said crab for moving said movable portions of said shell along the stationary ones to allow the passage of said crab, means for returning said movable portions into the closing position after said crab has passed, and an easily detachable mooring device for the dirigible capable of withstanding high tensional stresses and adapted to permit free motion of the dirigible towards 110 115 120 all sides mounted on said crab.

4. In a mooring device for dirigibles, in combination, a rotatable hangar, a mooring mast of lattice construction mounted above the aperture of said hanger, a stream line shell enclosing said mast, a travelling crab adapted to move along said mooring mast in a vertical direction, and an easily detachable mooring device for the dirigible capable of 125 130 withstanding high tensional stresses and

adapted to permit free motion of the dirigible towards all sides mounted on said crab, and means for mechanically opening said shell along its entire length to allow said travelling crab with the attached dirigible to pass and closing it after said crab has left said mast.

5. In a mooring device for dirigibles, in combination, a rotatable hangar, a mooring mast of lattice construction mounted above the aperture of said hangar, a stream line shell enclosing said mast, a travelling crab adapted to move along said mooring mast in a vertical direction, and a screw breech lock for mooring the nose of the dirigible within the frame of said crab, said lock comprising a bolt mounted on the nose of the dirigible and provided with interrupted screw thread and a nut mounted on said crab likewise with interrupted screw thread, the threaded sections of said nut corresponding with the bare sections of said bolt.

6. In a mooring device for dirigibles, in combination, a rotatable hangar, a mooring mast of lattice construction mounted above the aperture of said hangar, a stream line shell enclosing said mast, a travelling crab adapted to move along said mooring mast in a vertical direction, and a screw breech lock for mooring the nose of the dirigible within the frame of said crab, said lock comprising a bolt mounted on the nose of the dirigible and provided with interrupted screw thread and a nut mounted on said crab likewise with interrupted screw thread, and threaded sections of said nut corresponding with the bare sections of said bolt, and a worm gear for rotating said nut.

7. In a mooring device for dirigibles, in combination, a rotatable hangar, a mooring mast of lattice construction mounted above the aperture of said hangar, a stream line shell enclosing said mast, a travelling crab adapted to move along said mooring mast in a vertical direction, and a screw breech lock for mooring the nose of the dirigible within the frame of said crab, said lock comprising a bolt mounted on the nose of the dirigible and provided with interrupted screw thread and a nut mounted on said crab likewise with interrupted screw thread, the threaded sections of said nut corresponding with the bare sections of said bolt, a worm gear for rotating said nut, a guide funnel with two diametrically opposite guide slots located in front of said nut, and guide blades mounted on the nose of the dirigible adapted to engage said slots.

8. In a mooring device for dirigibles, in combination, a rotatable hangar, a mooring mast of lattice construction, mounted above the aperture of said hangar, a stream line shell enclosing said mast, a travelling crab adapted to move along said mooring mast in a vertical direction, and a screw breech lock

for mooring the nose of the dirigible within the frame of said crab, said lock comprising a bolt mounted on the nose of the dirigible and provided with interrupted screw thread and a nut mounted in a Cardan joint on said crab likewise with interrupted screw thread, the threaded sections of said nut corresponding with the bare sections of said bolt, a worm gear for rotating said nut, a guide funnel with two diametrically opposite guide slots located in front of said nut, and guide blades mounted on the nose of the dirigible adapted to engage said slots.

9. In a mooring device for dirigibles, in combination, a rotatable hangar, a mooring mast of lattice construction mounted above the aperture of said hangar, a stream line shell enclosing said mast, a travelling crab adapted to move along said mooring mast in a vertical direction, and a screw breech lock for mooring the nose of the dirigible within the frame of said crab, said lock comprising a bolt mounted on the nose of the dirigible and provided with interrupted screw thread and a nut mounted in a Cardan joint on said crab likewise with interrupted screw thread, the threaded sections of said nut corresponding with the bare sections of said bolt, a worm gear for rotating said nut, a guide funnel with two diametrically opposite guide slots located in front of said nut, and guide blades mounted on the nose of the dirigible adapted to engage said slots, ball bearings between the nut of said breech lock and said guide funnel and between said nut and the inner Cardan ring.

10. In a mooring device for dirigibles, in combination a rotatable hangar, a mooring mast of lattice construction mounted above the aperture of said hangar, a stream line shell enclosing said mast, a travelling crab adapted to move along said mooring mast in a vertical direction, and a screw breech lock for mooring the nose of the dirigible within the frame of said crab, said lock comprising a bolt mounted on the nose of the dirigible and provided with interrupted screw thread and a nut mounted in a Cardan joint on said crab likewise with interrupted screw thread, the threaded sections of said nut corresponding with the bare sections of said bolt, a worm gear for rotating said nut, a guide funnel with two diametrically opposite guide slots located in front of said nut, and guide blades mounted on the nose of the dirigible adapted to engage said slots, ball bearings between the nut of said breech lock and said guide funnel and between said nut and the inner Cardan ring, and springs for supporting said Cardan joint in relation to the frame of said crab.

In testimony whereof I affix my signature.
OTTO KRELL.
